UNITED STATES PATENT OFFICE.

MOSES M. MOORE, OF CHICAGO, ILLINOIS, ASSIGNOR TO THEODORE W. SNOW, OF CHICAGO, ILLINOIS.

STAND-PIPE.

SPECIFICATION forming part of Letters Patent No. 718,720, dated January 20, 1903.

Application filed July 15, 1902. Serial No. 115,680. (No model.)

To all whom it may concern:

Be it known that I, MOSES M. MOORE, a citizen of the United States, residing at Chicago, in the county of Cook and State of Illinois, 5 have invented a new and useful Improvement in Stand-Pipes, of which the following is a specification.

My invention relates to improvements in the construction of railway stand-pipes, more 10 especially of the general type exemplified in Letters Patent of the United States No. 547,692, granted to me October 15, 1895, and No. 682,106, granted to me September 3, 1901.

My present object is to provide certain improvements in the construction of valve mechanism at the base of the swinging column with a view more particularly to avoiding undue shock upon the base by a too-sudden cutting off of the flow of water when the valve 20 is closed.

In carrying out my invention I provide a cushioned seat of improved construction for the valve exposed to the water-pressure in such a manner that it will yield under a sudden rise of pressure when the valve is closed and neutralize shock.

Referring to the drawings, Figure 1 is a broken view showing the base portion of a stand-pipe in a vertical section, and Fig. 2 an enlarged broken section taken on line 2 in 30 Fig. 1.

A is a valve-casing forming the base of the stand-pipe structure. In one side of the casing A is an opening a to receive the end of 35 a water-supply pipe B. The opposite side of the casing A is open and fitted with a removable closing-plate in which there is a hand-hole b, closed by a removable cover b', to give ready access to the interior of the casing when 40 desired. The top portion c of the casing is circular, presenting a circular vertical opening c'.

C is the vertical axially-turning tubular column of the stand-pipe, which in practice carries a vertically-swinging horizontally-extending discharge-pipe portion and other parts which have no direct bearing upon the present invention, but may be seen by referring to my aforesaid Letters Patent No. 682,106.

50 C' is a cup-shaped base portion of the column C, provided on its under side with a

bearing projection d, adapted to rest upon a central bearing projection e in the base of the casing A. In the upper side of the base C' is a circular vertical guide-opening d', surrounded by a flange having ears d².

The column C is formed near its lower end portion with a smooth cylindrical outer surface f, which passes loosely through the guide-opening c' of the casing, the joint between the column and casing being rendered water-tight by a gasket or the like g, which does not interfere with the axial turning of the column.

Secured to the lower end of the tubular portion of the column C is a ring C², having perforated ears h, corresponding in number and position with the perforated ears or flanges d² of the column-base C'.

The column C and base C' are connected 70 together in rigid relation by means of bolts h', secured at opposite ends in the ears h d², as shown.

Fitting in the opening d' of the base C' is a vertically-movable disk or valve-seat D, provided with a central opening i and other openings i'.

In the base C' is a plate E, provided with a series of three or more upward-extending lugs E', surrounded by cushioning-springs E², on 80 which the disk or valve-seat D rests.

Screwed into or otherwise fastened in the center of the base C' is a bolt or post d³, threaded along its upper end portion, where it passes loosely through the opening i in the 85 valve-seat D. Nuts d⁴ on the upper end of the bolt d³ limit the upward movement of the seat D under the upward pressure of the cushioning-springs E².

Secured upon the upper face of the disk D 90 is a gasket D', having an inclined upper surface k, which forms the annular seating-face for the valve. Around the outer side of the gasket D' the seat D presents an annular horizontally-exposed face D² for the purpose hereinafter described.

F is a vertically-movable cylindrical water-column-supply valve mounted upon a spider F'. The spider is secured at its center to the lower end of a rod F², extending downward 100 from a bar or cross-head F³, which in turn is secured to valve-operating rods F⁴ F⁵ of the

construction shown in my aforesaid Letters Patent No. 682,106. The valve F fits and slides in the guide-ring C², the joint between the two being rendered water-tight by a 5 washer h². The lower end of the valve F presents an annular inclined meeting face l, corresponding in shape to the meeting face k of the valve-seat.

On opposite sides of the column C, below the 10 surface f, are antifriction-rollers f', adapted to move upon the under surface of an annular track g', fastened against the under side of the part c of the casing around the opening c'. In the side of the column in the position shown is a draining-opening m, leading to a short tubular valve-chamber m', in which works a vertically-movable cylindrical valve n, presenting a chamber having an inlet-opening n' and an outlet n². The valve n 15 is upon a rod n³, fastened at its upper end to a bracket n⁴ on the rod F⁵.

In practice water enters the casing A from the pipe B under an established head of pressure, which usually approximates about 20 seventeen pounds to the square inch. This pressure exerted in the casing against the under surface of the column-base C' is sufficient to raise the base, column, and parts carried thereby, so that the rollers f' will bear against 25 the track g', in which position the parts are sustained while the water-column-supply valve F is closed. To insure perfect watertight closing of the valve F, it should bear against the seat k with a certain degree of 30 pressure. The springs E² should have a combined resistance capable of sustaining the valve-seat device D under a pressure of, say, 35 seventeen pounds to the square inch exerted by the water upon the annular surface D² 40 supplemented by the said pressure exerted by the valve F against the annular seating-face k. In fact I prefer in practice that the springs should be capable of holding the part D against yielding under a pressure of five 45 pounds to the square inch in excess of the normal pressure of the water against the surface D² and of the valve against the surface k. In operation when the valve is closed the sudden stoppage of the flow of water produces 50 an accumulation of preponderating pressure from the water-supply, which unless means are provided to neutralize it produces a shock upon the parts, which in time affects the same injuriously and causes parts to leak. 55 The construction of the yielding valve-seat described overcomes this difficulty, because when the valve F is closed any sudden rise of pressure exceeding, say, five pounds above normal against the surface D² will press the 60 seat down against the resistance of the springs E² and permit the blow to spend itself by the

passage of a slight additional amount of water through the opening below the valve thus created. It is found in practice that without the cushioned seat D or equivalent neutralizing mechanism a sudden closing of the valve produces a jar creating a decided and pronounced trembling of the entire structure, while with my improved cushioning mechanism this shock is neutralized to a degree which renders it immaterial.

While I prefer to construct my improvements throughout as shown and described, they may be variously modified in the matter of details of construction without departing 75 from the spirit of my invention as defined by the claims.

What I claim as new, and desire to secure by Letters Patent, is—

1. In a stand-pipe, a water-column-supply 80 valve and its seat supported in yielding relation, and means enabling the separation of the seated valve and seat under excessive water-supply pressure.

2. In a stand-pipe, a water-column-supply 85 valve, a yieldingly-supported seat therefor, and means enabling the separation of the seat from the seated valve under excessive water-supply pressure.

3. In a stand-pipe, a cylindrical valve and 90 a seat therefor against which the valve bears at its end to close, the seat having an area exposed to the pressure of the water-supply when the valve is closed and being supported to yield away from the valve when said pressure is excessive.

4. In a stand-pipe, a column having a chambered base, a vertically-sliding cylindrical valve in the column with means for operating it, a seat for the valve yieldingly mounted 100 in said base and having an area exposed to the pressure of the water-supply when the valve is closed, whereby it will yield away from said valve when said pressure is excessive.

5. In a stand-pipe, a column having a cup-shaped base, a vertically-sliding cylindrical valve in the column with means for operating it, a valve-seat, springs in the base upon which said seat is mounted to yield in the 110 downward direction, the seat having on its upper side an annular seating-face for the valve, and an annular horizontally-disposed surface around the seating-face exposed to the pressure of the water-supply when the 115 valve is closed, the seat being supported by its springs to yield away from the valve under excess of said pressure.

MOSES M. MOORE.

In presence of—

ALBERT D. BACCI,
JOHN H. LEE.
